UNITED STATES PATENT OFFICE.

GEORGE H. ELLSBURY, OF TOWER CITY, DAKOTA TERRITORY.

GRAIN-SEPARATOR.

SPECIFICATION forming part of Letters Patent No. 339,631, dated April 13, 1886.

Application filed May 25, 1885. Serial No. 167,666. (No model.)

To all whom it may concern:

Be it known that I, GEORGE H. ELLSBURY, a citizen of the United States, residing at Tower City, in the Territory of Dakota, have 5 invented a new and useful Improvement in Grain Separators, of which the following is a specification.

Figure 1 is a vertical sectional view of the machine. Fig. 2 is a perspective view of the 10 machine. Fig. 3 is a plan and side view of the screen or sieve.

Similar letters refer to similar parts throughout the several views.

I make a rectangular or other convenient 15 shaped box, A, and on the sides of the box I secure one or more slanting partitions, K. Above this partition K, at a proper distance, I secure a screen or sieve, F, also set at an angle, and made of cast metal having ribs beneath to stiffen the body of the screen. I am 20 aware that metal screens have been used in grain-separators; but I prefer to make my screen of cast metal having ribs beneath it, as I desire to obtain rigidity and firmness, to 25 prevent sagging and an irregularity of surface. The sheet-metal screen is not sufficiently rigid to accomplish the purpose, while a cast-metal screen is. This screen F is perforated with round holes just large enough to allow grains 30 of cockle to pass through them, and the holes are so arranged in the screen that in passing in the direction of the arrow one hole will not immediately succeed the one next preceding it in the same line.

35 The screen F is so placed in the box A that the lower end projects through the side of the box, and just where it emerges there is a slit made, so that grain may escape through it. Above the screen and at both ends of it, when 40 in position in the box, are arranged two drums, one at each end, as D and D', D² D³, D⁴ D⁵, D⁶ D'. One of the drums, as D, has a prolonged axle, and on said axle is secured a driving-pulley, J, and to the projecting axle of the other 45 drum, as D', and to the feed-roller L is attached a belt, N, as shown in Fig. 2. About the drums D and D' is secured a polished steel or metal apron C. This apron is made preferably of steel, as the hardness of the metal 50 prevents its being worn out by friction, and the rigidity thereof prevents the grains of

wheat or other elongated grain from turning upon their ends, thus holding the grain flat down on the screen, which is very essential in separating cockle or round seed, as they will 55 roll over the screen and drop through the holes. An apron of canvas or other elastic material will not answer the purpose, as the grain is not held firm enough for the purpose of separation, and wheat is allowed to get 60 through the screen. A cleat or strip on the apron feeding the grain to the screen is far more objectionable than a canvas apron, as it does not keep the grain flat at all, which is the object in using an apron and pressure-boards, 65 and the drums D and D' are so adjusted that the lower face of the apron comes in contact with the face of the screen F. Between the upper and lower parts of the apron C is a pressure-board, E, which rests upon the apron C, 70 pressing it against the screen F. Secured to the pressure-board E are springs h, which are also secured to the board g, which is secured to the sides of the box A. The object of the springs h is to keep the apron against the 75 screen, and yet allow of the passage between the screen F and the apron C of bodies of unequal size and shape.

At the upper end of the box A, I place a hopper, B, which is triangular in shape, two 80 of the sides sloping to a point. At the lower end of the hopper I make an opening, which is partially closed by a fluted drum or roller, L. This fluted roll L is just above the screen F, and is connected by a small band or belt, 85 N, with the drum D', which imparts to it its motion.

The lower end of the partition K projects through the side of the box A, and beneath the projecting end of K is an angular trough, 90 a, which is inclined and slopes toward the funnels e in the pipe M.

Having thus described the parts of my machine I now proceed to describe its operation. Mixed grain is put into the hopper B, running down till it is arrested by the roll L. Motion is imparted to the pulley-wheel J, and that rotates the apron C, which imparts in its turn motion to the drum D', and this, through the belt N, to the fluted roll L. The revolution of the roll L feeds the grain down into the screen F, and gravity carries it down to

the drum D', where it is caught by the apron and carried down between the apron and the screen F. The pressure-boards E E' E'' E'', springs h h h, aprons C C C C, and screens F F F F keep the grains of wheat, oats, and rye on their flattened sides, while the cockle rolls over and over till it reaches a hole in the screen, when it is forced through and falls upon the inclined partition K, when it rolls 10 out of the slit in the side of the box into the trough a, thence into the pipe M, and is collected. The wheat or other grain slides over the screen F, and when finally freed from the apron falls outside of the machine and is collected. 15

I do not in this invention lay claim to grain-separators in the broad sense, as I am fully

aware that machines of this nature have been constructed with aprons, screens, hoppers, &c.

What I claim is—

A grain-separator comprising the hopper B, the fluted roll L, the cast-metal screen F, provided on its under side with stiffening-ribs, the endless steel apron C, the drums D D' on which said apron is mounted, means for actuating the feed-roll and drums, the pressure-board E, coiled springs h, and resistance-board g, located between the upper and lower sides of said endless apron, substantially as described. 20 25

GEORGE H. ELLSBURY.
